UNITED STATES PATENT OFFICE

92,176

DESIGN FOR AN ICE PICK

Delmar R. Hughes, Oakwood, Ohio

Application February 7, 1934, Serial No. 50,658

Term of patent 7 years

To all whom it may concern:

Be it known that I, DELMAR R. HUGHES, a citizen of the United States, residing in the city of Oakwood, in the county of Montgomery and State of Ohio, have invented a new, original, and ornamental Design for an Ice Pick, of which the following is a specification, reference being had to the accompanying drawing, forming part thereof.

The figure is a perspective view of an ice pick, showing my new design.

I claim:

The ornamental design for an ice pick, as shown.

DELMAR R. HUGHES.
